201,750

COMBINED CHAISE AND A SUNSHADE THEREFOR

Merle C. Melchior, Los Angeles, Calif., assignor of one-half to Sidney Galper, Los Angeles, Calif.

Filed Sept. 29, 1964, Ser. No. 81,919

Term of patent 14 years

(Cl. D15—11)

FIG. 1

FIG. 2

FIG. 3

FIGURE 1 is a perspective view of a combined chaise and a sunshade therefor embodying my new design;
FIGURE 2 is a top plan view thereof;
FIGURE 3 is a front end elevational view thereof;
FIGURE 4 is a side elevational view thereof; and
FIGURE 5 is a rear end elevational view thereof.

I claim:

The ornamental design for a combined chaise and a sunshade therefor, as shown.

References Cited by the Examiner

UNITED STATES PATENTS

D. 120,131 4/40 Moeller ----- D15—11

OTHER REFERENCES

House and Garden, April 1960, page 195, convertible chaise at center by John Hancock.

House Beautiful, April 1961, page 31, chaise at upper right by Patio Sales.

EDWIN H. HUNTER, Primary Examiner.